UNITED STATES PATENT OFFICE.

JOHN ADAM GOETZ, OF BROOKLYN, NEW YORK.

MEMORY-RING.

SPECIFICATION forming part of Letters Patent No. 581,549, dated April 27, 1897.

Application filed May 23, 1896. Serial No. 592,705. (No model.)

To all whom it may concern:

Be it known that I, JOHN ADAM GOETZ, a citizen of the United States, residing at Brooklyn, in the county of Kings and State of New York, have invented certain new and useful Improvements in Memory-Rings; and I do hereby declare the following to be a full, clear, and exact description of the invention, such as will enable others skilled in the art to which it appertains to make and use the same.

My invention relates to improvements in finger-rings, the object of the same being to produce what I term a "memory-ring," to assist the wearer thereof to remember certain things that he may have to do or certain places that he may have to go.

The invention consists of a plurality of rings of equal size, each having a series of letters stamped on its outer edge, the same being adapted to fit within a ring of larger diameter and be held thereto by frictional contact. The inner rings are provided with lugs or projections for turning them to bring one of the letters thereon into view.

The invention is clearly illustrated in the accompanying drawings, in which—

Figure 1 represents an elevation of my memory-ring with all the parts assembled. Fig. 2 is a cross-section through the same. Fig. 3 is a perspective view of one of the inner rings detached. Fig. 4 is a similar view of the outer ring detached.

Like reference-numerals indicate like parts in the different views.

My improved memory-ring is made up of a plurality of narrow rings or bands 1, each having stamped upon its outer periphery a series of letters 2, as clearly shown in Figs. 1 and 3. These rings or bands 1 are also formed with projections 3 thereon, by means of which they may be turned, as hereinafter described. The rings 1 are inclosed by an outer band or ring 4, which is as wide as the combined width of the rings 1 and is formed with a narrow connecting-strip 5, as shown.

The rings or bands 1 are held within the band

4 by frictional contact, the same being adapted to be turned by means of the pins or projections 3 thereon.

In using my device set the inner rings 1 so that one letter on each ring will project between the ends of the band 4, the letters selected being the initial letter of some errand that is to be performed, some purchase that is to be made, or any other thing that the wearer may desire to be reminded of. For example, if an order for groceries has to be given and the doctor is to be called the letter "G," standing for grocer, and the letter "D," standing for doctor, will be brought so that they will be seen through the space between the ends of the band 4.

The ring may be made of gold, silver, or other suitable metal, and as many of the inner bands 1 may be employed as desired.

It should be stated that the letters on the bands 1 may be those of any language, and that the said bands may be further provided with blanks which will be brought to view between the ends of the band 4 when there is nothing that the wearer is to be reminded of.

What I claim as new, and desire to secure by Letters Patent, is—

The herein-described memory-ring, made up of an outer band the ends of which are connected by a narrow strip forming open spaces on each side thereof, and a plurality of inner bands in frictional contact therewith, each of said inner bands having a series of letters upon its outer periphery, one letter only on each band being visible at a time through said openings, and lugs or projections on said inner bands whereby the same may be turned, as and for the purpose set forth.

In testimony whereof I have signed this specification in the presence of two subscribing witnesses.

JOHN ADAM GOETZ
